US00D789471S

(12) **United States Design Patent** (10) **Patent No.:** **US D789,471 S**
(45) **Date of Patent:** **** Jun. 13, 2017**

(54) **WATER FILLED PUNCHING BAG**

(71) Applicant: **Taylor Made Group, LLC**,
Gloversville, NY (US)

(72) Inventors: **Jason Pajonk-Taylor**, Saratoga
Springs, NY (US); **Edwin Rivera**, East
Northport, NY (US)

(73) Assignee: **TAYLOR MADE GROUP, LLC**,
Gloversville, NY (US)

(**) Term: **15 Years**

(21) Appl. No.: **29/580,803**

(22) Filed: **Oct. 13, 2016**

Related U.S. Application Data

(63) Continuation of application No. 29/571,880, filed on
Jul. 22, 2016, which is a continuation-in-part of
application No. 29/498,739, filed on Aug. 7, 2014,
now abandoned.
